UNITED STATES PATENT OFFICE.

ARTHUR R. WILFLEY, OF DENVER, COLORADO.

CONCENTRATOR.

1,097,113.

Specification of Letters Patent.

Patented May 19, 1914.

Application filed February 3, 1912. Serial No. 675,302.

To all whom it may concern:

Be it known that I, ARTHUR R. WILFLEY, citizen of the United States, residing in the city and county of Denver and State of Colorado, have invented certain new and useful Improvements in Concentrators; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in concentrators, of the general construction set forth in my previous application, Serial No. 606,196, filed February 2, 1911; now Patent No. 1,021,961, granted April 2, 1912; and also my application Serial No. 656,318, filed October 23, 1911, now Patent No. 1,056,388, granted March 18, 1913.

In my improved apparatus, tilttable tables are employed, each containing a plurality of decks. These tables while at their upward limit of movement are slightly inclined rearwardly, forming a sort of pocket, whereby the pulp is caused to accumulate upon the decks of the tables during the early part of the treatment of the charge, provision being made for subsequently tilting the tables gradually at first and later more abruptly. The final tilting movement coöperates with an additional supply of water to discharge the concentrates from the tables.

In my improved construction, the downward movement of the tables, by virtue of a suitable connection between a valve and the tables, opens the valve to permit an additional supply of wash water to facilitate the rapid removal of the concentrates while the table is at its downward limit of movement, or at its greatest inclination.

Another feature of novelty consists in the employment of a deflector controlled by a cam, which operates in harmony with another cam for controlling the movement of the tables. The first named cam serves to actuate the deflector, whereby the pulp is directed upon the table as it is raised to its upward limit of movement, and cut off from the other table.

Other features of novelty embraced in my present improvement, will be fully set forth in the detail description.

Having briefly outlined my improved con-

struction, I will proceed to describe the same in detail, reference being made to the accompanying drawing, in which is illustrated an embodiment thereof.

In this drawing: Figure 1 is a central vertical section taken through the apparatus on the line 1—1, Fig. 7. Fig. 2 is a detail view on a larger scale, illustrating a trough construction for supplying water to the tables, and showing one of the automatically operated valves employed in connection therewith. This may be termed a section taken on the line 2—2, Fig. 7, viewed in the direction of the arrow. Fig. 3 is a section taken on the line 3—3, Fig. 7, looking toward the left. Fig. 4 is a detail view, illustrating the manner of pivotally mounting the tables. This is a view looking in the direction of arrow 4, Fig. 5. Fig. 5 is a section taken on the line 5—5, Fig. 3, the parts being shown on a larger scale. Fig. 6 is a section taken approximately on the line 6—6, Fig. 1. Fig. 7 is a top plan view of the apparatus with parts removed. It is also a section taken on the line 7—7—, Fig. 1, looking downwardly. Fig. 8 is a top plan view of the construction, partly in section, with parts removed from above for the purpose of more clearly illustrating the manner of pivotally supporting the two table members.

The same reference characters indicate the same parts in all the views.

Let the numeral 5 designate a suitable frame work, which extends upwardly and forms the support for the mechanism for discharging pulp and wash water upon the tables. This apparatus includes two troughs 6, the said troughs being supplied with water from a conduit 7, which discharges into a trough member 8 communicating with the troughs 6 by diverging branches 9. Mounted above the water supply, troughs, or launders 6, and arranged transversely thereof, are two bars 10, upon which rest the opposite ends of a pulp deflector 12, which is V-shaped, in cross section and adapted to alternately feed the pulp to the two table members 13, as hereinafter more fully described.

A pulp distributer 14 is mounted above the deflector, the distributer being stationary. When the deflector is in the position shown at Fig. 1, viz., the farther toward the left, the pulp from the discharge board, or plate 15, passes to the inclined surface 16 of the deflector, and thence into the sub-

- divider 17, for carrying the pulp to the various decks 18 of the table farther toward the right, the said table being at its upward limit of movement and slightly rearwardly inclined, or tilted toward the longitudinal center of the apparatus, whereby a quantity of pulp will accumulate upon the various decks of the table before any can escape from the forward edges of the said decks.
- 5 10 This accumulation of pulp upon the table decks when the table is at its upward limit of movement, is indicated by dotted lines 19, in Fig. 1.
- 15 As illustrated in Fig. 1, the table 13, toward the left, is at its downward limit of movement. Now, when this table member is raised, the deflector will be shifted from the full line position in Figs. 1 and 2, to the dotted line position in Fig. 3, whereby the 20 pulp from the distributor will fall upon the opposite inclined surface 20 of the deflector, whereby the pulp will fall into the sub-divider 17 of the table 13 farther to the left in Figs. 1 and 3.
- 25 30 The mechanism for accomplishing the shifting of the deflector, will now be described: An eccentric cam 21 is mounted on a longitudinally disposed shaft 22 journaled at its opposite ends in the lower part of the frame work, as shown at 23. This shaft carries a fast gear 24 which meshes with a pinion 25 fast on a shaft 26, carrying a worm-wheel 27 operated from a worm carried by a shaft 28, the 35 last named shaft being actuated by a cone pulley 29 engaging a pulley 30 fast on the shaft 28. The cone pulley 29 is fast on a shaft 31, and is initially operated by connecting a pulley 32 thereon with any 40 suitable motor. Upon the shaft 22, and near opposite ends thereof, are located two cams 21, each having a groove 33, which is engaged by a roller 34, pivoted on the lower extremity of a relatively long lever 35, the latter being fulcrumed intermediate its extremities, as shown at 36, the fulcrum pin passing through the said lever and perforations formed in the bifurcated extremity 37 of a bracket 38, secured to the frame work, as shown at 39. The upper extremities of the two levers 35 are provided with slots 40, which are engaged by pins 41, with which the opposite extremities of the deflector 12 are equipped. The slots 33 of 45 the cams 21, are so arranged with reference to the center of motion of the axis of the shaft 22, that when the cam is in the position shown in Fig. 3, the lower extremities of the levers 35 will be moved toward the left 50 a sufficient distance to cause the deflector 12 to occupy the full line position in Figs. 1 and 3. This condition will continue while the cams are making approximately one-half of a revolution, after which the anti-frictional rollers 34, will enter the other por-

tion of the cam slots which are farther from the center of motion, which will shift the lower arms of the levers 35 far enough toward the left to move their upper arms toward the right, whereby the deflector is caused to assume the dotted line position in Fig. 3, whereby the pulp from the distributor 14 will be caused to fall on the opposite inclined surface 20 of the deflector, and the pulp will be guided to the sub-divider 17 of the table member farther toward the left. (See Figs. 1 and 3.)

The inclination of the tables is controlled by levers 42, fulcrumed at 43, and having anti-frictional rollers 44 engaging the irregular peripheral faces of cams 45, fast on the shaft 22. The lower extremities of the levers 42 are curved outwardly from the shaft 22, and are equipped with cups 46, adapted to receive the ball extremities 47 of rods 48, whose upper extremities 49 are ball-shaped and enter cups 50, secured to the lower surface of the lowermost decks of the table. The rods 48 are each composed of two members connected by turnbuckles 51, for convenience of adjustment.

When the cam 45 is in the position illustrated in Fig. 1, the table at the left is at its downward limit of movement, and the table at the right is at its upward limit of movement. In this event, the roller 44 of the lever 42 farther toward the left engages a recess, or depression, 52, formed in the face of the cam, the bottom of this depression being the point on the face of the cam nearest the axis of the shaft 22. In describing this operation, it is assumed that the cam 45 is traveling in the direction of the arrow in Fig. 1. From an inspection of the cam it will be understood that the roller 44 of the said lever, no sooner reaches the bottom of the recess 52, which recess occupies but a small part of the face of the cam, than it begins to leave said recess, being quickly forced outwardly to a part of the cam considerably farther from the center of motion. While the said roller is traveling from the bottom of the recess 52 to a point 53 on the face of the cam, the table 13 on the left (see Fig. 1) will be raised to its limit of upward movement, and will remain in this position while the cam is making approximately three-fourths of a revolution. In the meantime, however, the recess 52 of the cam, after having made approximately one-half of a revolution from the position illustrated in Fig. 1, will be in position to allow the roller 44 of the opposite lever to enter the said recess, thus allowing the table toward the right to assume its greatest position of inclination. It will thus be seen that both tables are for a considerable time simultaneously at their upward limit of movement.

When each table is at its upward limit of

movement it receives water from one of the troughs, or launders, 6 only, and this wash water mingles with the pulp during the period of stratification, so to speak, or while 5 the separation of the concentrates is taking place, by settling to the bottom of the quantity of pulp which has accumulated on the table. During the time that the pulp is being fed to a table, when the latter is at its 10 upward limit of movement, the wash water from the conduit 7 is cut off from the table by means of an oscillating gate 54, pivoted at 55, its outer extremity at 56 being adapted to alternately engage the opposite side 15 walls of the receptacle 8. The opposite end of this gate is slotted, as shown at 57, to receive an extension 58 of one of the pins 41 of the deflector 12, the said pin having an upwardly projecting portion entering the 20 bifurcated extremity 57 of the gate, hence, as the deflector is shifted toward the left, (see Fig. 1) to cause the pulp to enter the sub-divider 17 of the right hand table, the 25 gate 54 is shifted to cut off wash water from the right hand launder 6, which supplies the right hand table, allowing all of the water from the conduit 7 to pass to the launder 6 which supplies the left hand table. At the same time, the left hand table, which 30 is in the lowermost position, receives an additional supply of wash water from an auxiliary launder 59, which is composed of two members 60, arranged parallel with the launders 6, but farther from the longitudinal 35 center of the machine, the two launder members 60 being connected at one end by a transverse member 61. This auxiliary launder 59 is constantly supplied with wash water from a conduit 62 arranged at one end 40 of one of the launder members 60. Each of the launder members 60 is provided with two valves 63 which control openings 64, forming communication between the launder members 60 and the launders 6. These 45 valves close by gravity, being of sufficient mass for the purpose. Each valve is connected by means of a link 65 with a lever 66, fulcrumed at 67, the arm of the lever remote from the valve, being connected with 50 one extremity of a chain 68, the opposite extremity of the chain being connected with a table member, as shown at 69. Normally, or when the table are at their upward limit of movement, these valves are 55 closed, whereby the water from the auxiliary launder 59 is cut off from the launders 6. When, however, either table is tilted, these valves 63 of the launder member 60 on the side where the tilted table is located, 60 are opened to allow the water from the launder 69 to enter the launder 6, whereby an increased amount of wash water is discharged upon the decks of the tilted table to facilitate the removal of the concentrates 65 therefrom. However, as soon as the table

has moved upwardly a short distance, the chains 68 slacken, and the valves 63 seat themselves by gravity, and cut off the excess supply of wash water to the launder 6.

Each table is provided on each side with 70 a plate 70, which is secured to the table by means of bolts or other suitable fastening devices 71. Each of these plates carries a conical journal 72, which engages a bearing 73 of counter-part shape, adjustably mounted on one extremity of a bar 74, the said bar connecting the two tables, there being one of these connecting bars at each end of the table structure. The bearing member 73, includes a plate member 75, which is connected with the bar 74 by bolts 76, the said bolts passing through slots 77 formed in the bar; the bearing member 73 passes through a relatively large opening 78 formed in the bar. By virtue of this construction, the bearings for the journals 72 are adjustable longitudinally of the bar 74, which is necessary or highly advantageous in assembling the structure.

A rod 79 passes between the two tables in 90 a lengthwise direction and passes through openings 80 formed in the centers of the two bars 74. At one extremity, this rod is connected with the bar by a nut 81, while at its other extremity, the rod is threaded, 95 as shown at 82, and extends beyond the bar, where it is connected with a ball cup member 83, co-operating with a similar member 84, the two members being secured together by bolts 85 and forming a bearing 100 for the ball extremity 86 of a pitman 87 connected with a strap 88 of an eccentric 89 mounted on the shaft 31, which imparts the transverse vibration of reciprocatory movement to the two table members. This 105 movement is simultaneously imparted to both tables through the agency of the rod 79. In order to make the bars 74 connecting the two tables, as aforesaid, substantially rigid, the tables are reinforced on opposite 110 sides of the tables at the center of each bar by blocks 90, which fill the space between the bars and the tables, since the bars are held at some distance from the tables by virtue of the bearing construction for their 115 journals 72.

The tables are movably supported from underneath by elongated bearings 91, formed on the frame work, the said bearings having grooves length-wise of the bearings, in 120 which are located removable blocks 92, secured in place by bolts or other suitable fastening devices, 93; these blocks are grooved to receive wearing members 94, which are semi-cylindrical in shape and open at the top to receive elongated projections 95, which are formed integral with plates 96, secured to the under surface of the lowermost deck of each table, as shown at 97. The wearing parts 94 are closed at their ends, 125 130

and the projections 95 fit closely therein, so that during the longitudinal reciprocation of the tables, the wearing parts move with the projections. Attention is called to the 5 fact that this construction for supplying the tables, acts in harmony with the journal bearing construction arranged at the ends of the tables, as heretofore described. In other words, the axis of the journal 72, is 10 coincident with the center of motion of the tables on the supporting structure underneath, as heretofore described.

As illustrated in the drawing, provision is made for receiving the discharge of the 15 gangue and concentrates when the tables are tilted. This construction includes two troughs, or receptacles, arranged on opposite sides of the structure. The outer trough 98, on each side, is arranged to receive the concentrates, while the inner trough 99, is adapted to receive the gangue. These two troughs virtually compose a receptacle divided into two compartments by a partition 100. Supported by upwardly 20 extending parts 101 and 102, is a stationary receptacle 103, provided at its bottom with a discharge nozzle 104, upon which is pivotally mounted, as shown at 106, a member 105, which is arranged to oscillate so as to 25 discharge into either of the compartments 98 or 99, as may be desired. Each oscillating member 105, is pivotally connected, as shown at 107, with a relatively long arm 108, which extends inwardly toward the 30 center of the machine, and is pivotally connected at its inner extremity, as shown at 109, with a lever arm, 110, carrying a roller 112 engaging an eccentric groove 113 in a cam 114, fast on the shaft 22. The upper 35 extremity of the lever arm 110, is pivotally mounted on the frame work, as shown at 115.

The construction of the cam 114 is such that during the operation of the machine, 40 the oscillating member 105 is shifted to discharge the concentrates from each table into the compartment 98, and to discharge the gangue into compartment 99 on each side of the structure.

50 From the foregoing description, the use and operation of my improved construction will be readily understood.

Assuming that the tables are in the relative position illustrated in Figs. 1 and 3, 55 the operation may be described as follows: The concentrates have just been discharged from the left hand table, since the latter is at its downward limit of movement, the said concentrates passing into the concentrate 60 compartment 98; while the table on the right, which is at its upward limit of movement has its rear side, or that nearer the center of the structure, slightly below its outer or discharge side, and by virtue of this arrangement, the pulp will accumulate on each

deck of the table, as indicated by the dotted lines 19, until the depth is sufficient to permit an overflow at the discharge side of the decks. During this accumulation, the metallic values under the influence of the vibration to which the table is subjected, as heretofore described, will settle on the upper surface of the decks, while the gangue, or worthless material, will remain in suspension in the water, and as soon as the overflow commences, the gangue only, will be discharged. This gangue discharge will continue during the first or initial tilting movements of the tables; the gangue, however, is quickly discharged, since it is held in suspension by the water, and as the table continues its tilting action, the valves 63 in the auxiliary launder will be opened, whereby the water from the auxiliary launder is allowed to enter the launder 6 on the corresponding side of the machine, whereby an additional quantity of water will be discharged through the outlet pipes or chutes 116, which lead from the perforations 117 in the bottom of each launder 6. This excess of water coöperates with the inclination of the table to quickly remove the concentrates from the decks of the latter, after which the table by virtue of the cams 45 and the connections between the cams and the table, as heretofore described, will be quickly raised to the normal position, or that shown at the right in Figs. 1 and 3, whereby the accumulation of pulp upon the various decks commences. Simultaneously with the 90 elevation of the table to its upward limit of movement, the deflector 12 is automatically shifted through the instrumentality of the lever 35 and the cam 21, whereby the discharge of pulp from the distributor will be 95 cut off from one table and discharged upon the other. Furthermore, as soon as the deflector is shifted from the full line position to the dotted line position (see Fig. 3), whereby, the pulp is caused to discharge 100 upon the left hand table, the gate 54 is automatically actuated to cut off the supply of water to the table on the left, and direct the wash water to the table on the right, whereby, this water is utilized for separating the 105 concentrates from the gangue, and finally in conjunction with the additional supply received from the auxiliary launder, serves to facilitate the discharge of the concentrates from the table when the latter is 110 tilted to the desired inclination, as heretofore explained.

In further explanation of the operation of my improved construction, it may be stated that the tables may be said to occupy three positions, viz., a rearward inclination and two forward inclinations. The rearward inclination is occupied by the table during the greater portion of the time, being the time during which the pulp is fed 115

to the table, and while the stratification of the material is taking place upon the table, whereby the metallic values are caused to settle upon the concentration faces of the 5 decks. During the rearward inclination of the table, or the position of the latter when its side adjacent the center of the machine is lowermost, the mineral values under the influence of the longitudinal reciprocation, 10 or vibratory movement of the table, not only settle upon the faces of the decks, but also travel rearwardly thereon, whereby when the table is given its initial forward inclination for the purpose of removing the 15 gangue, the mineral values are so far in the rear that they are prevented from escaping with the gangue.

Attention is called to the fact that the rear side of the table is closed against the 20 escape of either gangue or concentrates. After the material has been stratified upon the table during its rearward inclination, as heretofore explained, and the feed of the pulp to the table has been cut off, the table 25 assumes its first position of forward inclination, viz., during the time that the cam 45 is traveling from the point A to the point B in contact with one of the rollers 44 of a lever 42. During this time the gangue is 30 discharged from the table, since it is held in suspension by the water and readily escapes from the concentrates which are heaviest and form an approximately solid mass in direct contact with the faces of the decks. 35 After this discharge of the gangue, and during the time that the cam 45 is traveling from the point B to the bottom of the recess 52 on the face of the cam in contact with one of the rollers 44, the table drops to its 40 downward limit of movement, whereby it assumes its position of greatest inclination. It is during this time that the excess of wash water, due to the opening of the valves 63 of the launder members 60, occurs, 45 the increase of wash water coöperating with the increased inclination of the table to facilitate the discharge of the concentrates, the concentrate discharge being completed while the table is in its lowermost position, 50 or its position of greatest inclination. As the cam 45 continues its movement in the direction of the arrow (see Fig. 1), it quickly travels in contact with one of the rollers 44 from the bottom of the recess 52 to the 55 point 53 on the face of the cam, during which time the movement of the table just described has been reversed, and the latter is returned to its position of rearward inclination, which position it retains while 60 the cam 45 is traveling from the point 53 to the point A in contact with the roller 44 of the lever 42, which regulates the position of the table in question. When the rod 79 is applied to the bars 74, and fastened by the nut 81, the said bars are placed

under tension by the application of the nut. This feature, together with the blocks 90, causes the tables to be reciprocated in perfect unison, since the force employed in imparting the reciprocating movement is distributed throughout the entire length of the bars 74, the said bars being connected with the tables with reference to the center of gravity of the latter, whose rear sides, or the sides adjacent the center of the machine, 75 are heaviest.

By virtue of the construction described, for imparting the longitudinal reciprocation to the tables, the latter are maintained at all times in their normal operative positions, whereby all tendency to torsional strain, which would result from applying the power, in a less advantageous manner is overcome.

Having thus described my invention, what 85 I claim, is:

1. The combination of a tiltable concentrating table, closed at its rear side and open at its opposite side for discharge purposes, and means for automatically tilting the 90 table for two positions of successively greater inclination in a forward direction for the purpose of discharging the gangue and concentrates, respectively, and in the order named, and then reversing the table's 95 movement, and finally tilting it rearwardly to permit the accumulation thereon of a charge of pulp, and means for supplying pulp to the table during the period of rearward inclination, substantially as described. 100

2. The combination of a tiltable concentrating table, closed at its rearward side and open at its opposite side for purposes of gangue and concentrates discharge, means for automatically tilting the table to two 105 positions of successively greater inclination in a forward direction and then reversing the table's movement, and finally tilting it rearwardly to permit the accumulation of a charge of pulp thereon, means for supplying pulp during the period of rearward inclination, and means for cutting off the pulp during the period of forward inclination, substantially as described. 110

3. The combination of a tiltable concentrating table, closed at its rear side and open at its opposite side for purposes of gangue and concentrates discharge, means for automatically tilting the table to two positions of successively greater inclination in a forward direction, and then reversing the table's movement, and finally tilting it rearwardly to permit the accumulation of a charge of pulp thereon, means for supplying pulp during the period of rearward inclination, means for cutting off the pulp during the period of forward inclination, and means for supplying wash water during the period of forward inclination. 125

4. The combination of a tiltable concen- 130

- trating table, closed at its rear side and open at its opposite side for purposes of gangue and concentrates discharge, means for automatically tilting the table to two positions 5 of successively greater inclination in a forward direction, and then reversing the table's movement, and finally tilting it rearwardly to permit the accumulation of a charge of pulp thereon, means for supplying 10 pulp during the period of rearward inclination, means for cutting off the pulp during the period of forward inclination, means for supplying wash water during the period of forward inclination, and means for cutting off wash water during the period of rearward inclination.
5. The combination of a tilttable concentrating table, closed at its rear side and open at its opposite side for discharge purposes, means for tilting the table to two positions 20 of successively greater inclination in a forward direction for discharging the gangue and concentrates, respectively, in the order named, and then reversing the table's movement, and finally tilting it rearwardly to permit the accumulation thereon of a charge of pulp, means for supplying pulp during the period of rearward inclination, means for cutting off the pulp during the 30 period of forward inclination, means for supplying wash water during both periods of forward inclination, and means for supplying an additional volume of wash water during the period of greatest inclination.
- 35 6. The combination of a tilttable concentrating table, closed on its rear side and open at its opposite side for discharge purposes, means for automatically tilting the table to positions of successively greater inclination 40 in a forward direction for the purpose of discharging the gangue and concentrates therefrom, in the order named, and then reversing the table's tilting movement, and finally tilting it rearwardly to permit the 45 accumulation thereon of a charge of pulp, means for supplying pulp to the table during its period of rearward inclination, means for cutting off the supply of pulp from the table during the periods of forward inclination, means for supplying wash 50 water to the table simultaneously with the cutting off of the pulp therefrom, and means for automatically increasing the supply of wash water during the last period of forward inclination, for the purpose set forth.
- 55 7. The combination of a tilttable concentrating table, closed at its rear side and open at its opposite side for discharge purposes, means for tilting the table longitudinally to positions of successively greater inclination in a forward direction, and then reversing the table's movement, and finally tilting it longitudinally rearwardly to permit the accumulation thereon of a charge of

pulp, and means for imparting a transverse 65 reciprocating movement to the table.

8. The combination of a longitudinally tilttable concentrating table, closed at its rear side and open at its opposite side for purposes of gangue and concentrates discharge, 70 means connected with the table to tilt the latter to a position of rearward inclination and to two positions of successively forward inclination and maintain the inclinations for predetermined periods, means for supplying 75 pulp during the period of rearward inclination and for cutting off of pulp during the period of forward inclination, and means for supplying wash water during the two periods of forward inclination. 80

9. The combination of a tilttable concentrating table, a cam having three faces, means connected with the table and bearing upon said cam, the faces of the cam being proportioned to tilt the table to a position 85 of rearward inclination, and two positions of successively greater forward inclination and maintain the inclinations for predetermined periods, means for supplying pulp during the period of rearward inclination 90 and for cutting off the supply of pulp during the periods of forward inclination, and means for supplying wash water during the two periods of forward inclination.

10. The combination of a tilttable concentrating table, a cam having three faces, means connected to the table and bearing upon said cam, the faces of the cam being proportioned to tilt the table to a position 95 of rearward inclination and two positions of successively greater forward inclination and maintain the inclinations for predetermined periods, means for supplying pulp during the period of rearward inclination 100 and for cutting off the supply of pulp during the two periods of forward inclination, and means for supplying water during the two periods of greater inclination, the relative lengths of the three faces being such that the time during which the table is maintained in the position of rearward inclination is relatively long, while the times during 110 which it is maintained in the two positions of forward inclinations are relatively short and approximately equal. 115

11. The combination of a tilttable concentrating table, means connected with the table to tilt the latter to a position of rearward inclination and two positions of successively greater forward inclination, and 120 maintain the inclinations for predetermined periods, means for supplying the pulp during the period of rearward inclination and for cutting off the supply during the period of forward inclination, means for supplying 125 the table with wash water during the two periods of forward inclination, and means connected with the table and acted on by

the latter during its last position of forward inclination for automatically increasing the supply of wash water to the table, substantially as described.

5 12. The combination of a tiltable concentrating table, a cam having three faces, means connected with the table and bearing upon said cam, the faces of the cam being proportioned to tilt the table to a position 10 of rearward inclination and two positions of successively greater forward inclination, the faces of the cam varying in length, and their relative lengths being such that the table is maintained in the first position relatively long, and in the second and third positions relatively short, means for supplying 15 pulp during the period of rearward inclination, means for cutting off the supply during the periods of greater inclination and 20 means for supplying water during two periods of forward inclination.

13. The combination of a tiltable concentrating table, closed at its rear side and open

at its opposite side for purposes of gangue and concentrates discharge, a cam having 25 three faces, a connection between the cam and the table, the faces of the cam being proportioned to tilt the table to a position of rearward inclination and two positions of successively greater inclination and maintain the inclinations for predetermined periods, and having actuating means timed to harmonize with the tilting means for supplying pulp to the table during the period of rearward inclination, and for cutting off 30 the supply during the periods of forward inclination, and means for supplying wash water during the periods of forward inclination.

In testimony whereof I affix my signature 40 in presence of two witnesses.

ARTHUR R. WILFLEY.

Witnesses:

A. J. O'BRIEN,
A. EBERT O'BRIEN.
